UNITED STATES PATENT OFFICE.

WILLIAM H. CADWELL AND JOHN OTT, OF NEW BRITAIN, CONNECTICUT, ASSIGNEES
TO THE BEATON & CADWELL MANUFACTURING COMPANY, OF NEW BRITAIN, CONNECTICUT, A CORPORATION OF CONNECTICUT.

FIXED-TIME FLUSH VALVE.

Application filed April 15, 1926. Serial No. 102,237.

This invention relates to flush valves, and more particularly to a flush valve which will give a definite fixed period of flush irrespective of the length of time the actuating button is pressed down.

One object of this invention is to provide a flush valve of the above nature which will deliver only a single flush even though the actuating button may be operated a plurality of times in quick succession, or may be held down continuously.

A further object is to provide a flush valve of the above nature which will be simple in construction, fool proof, inexpensive to manufacture, easy to install and manipulate, ornamental, and very efficient and durable in use.

With these and other objects in view there have been illustrated on the accompanying drawings three forms in which the invention may be conveniently embodied in practice.

Fig. 1 represents a vertical side sectional view of a flush valve embodying the invention.

Fig. 2 is a side view of the top of a flush valve having a modified form of actuating means—in this instance a lever.

Fig. 3 is a side view, shown partially in section, of a flush valve having another modified form of actuating means—in this instance an oscillating handle.

Referring now to the drawings in which like reference numerals denote corresponding parts throughout the several views, the numeral 10 indicates the body member of the flush valve, said body member having a side inlet port 11 and a bottom outlet port 12. The top of the outlet port 12 terminates in an annular rim 13 which forms a seat for a main valve 14. The main valve 14 has a flat disc section 14^a having an upwardly extending shaft 15, said shaft 15 being preferably cylindrical in cross-section.

The disc section 14^a is also provided with a depending threaded shaft 16, surrounding which is a circular flexible annular diaphragm 17, preferably of rubber, which is adapted to seat tightly upon the rim 13, and is held in place by a tapered nut 18 screwed upon the lower end of the threaded shaft 16.

The outer edge of the diaphragm 17 is seated in an annular recess formed on the in-

side of a flange 19 of the body member 10, and said diaphragm is held rigidly upon said flange by the outer rim 20 of a cover member 21, said flanges 19 and 20 and said diaphragm 17 being held together tightly by a plurality of screws 22.

The space in the flush valve below the diaphragm 17 will hereinafter be termed the "main chamber", while the space between the diaphragm and the cover member 21 will be designated as the "control chamber".

The cover member 21 is provided with a central upwardly extending tubular section 23, said tubular section being reduced in diameter at its top portion 24. A pair of oppositely disposed apertures 24^a are provided in the sides of said reduced section 24 and a third aperture 24^b is provided in the top thereof. At the shoulder between the reduced section 24 and the tubular section 23, a beveled annular valve seat 25 is provided for a releasing valve which is adapted to fit tightly in said seat.

The releasing valve comprises a vertical rod 26 having a flange 27 near its bottom end, the portion of said rod below said flange 27 being threaded at 28 to receive a conical flexible valve washer 29, said washer 29 being held in place by a nut 30 screwed upon the threaded portion 28 of said rod 26. An operating button 31 is secured upon the top of the rod 26 preferably by a threaded section 31^a of said rod, said button 31 being preferably constructed from porcelain or other durable waterproof material. The button 31 is provided on its under side with a reinforcing disc 32, said disc 32 forming a bearing surface for a spiral spring 33 which surrounds said rod 26 and the reduced section 24 of the cover member.

In order to centralize the button member 31, said member is provided with a downwardly extending tubular skirt member 34, said skirt member being adapted to fit loosely within the upper cylindrical portion 35 of a conical shell member 36, said shell member 36 being enlarged and threaded at its base 36^a so that it may be screwed upon the outside of the flange 19 previously mentioned. The lower part of the flush valve is covered by a second shell member 37, having a threaded upper flange 37^a screwed to the

body member 10. The shell member 37 is provided with a threaded lower section 38 for connection to a pipe, not shown, said pipe leading to a closet bowl or other device to be flushed.

In order to provide means for producing a definite fixed period of flush irrespective of the length of time the operating button 31 is held down, a check valve member 39 is provided. The check valve member 39 comprises a cup-shaped upper main body portion 40 preferably cylindrical in shape and having a plurality of parallel ribs 41—eight in this instance—spaced uniformly about its periphery and adapted to seat within the cylindrical bore of the lower part of the tubular section 23 of the cover member 21.

The check valve member 39 is provided with a bottom horizontal flange 42 adapted normally to rest upon the top of the flat disc section 14^a of the main valve 14. When the flush valve has been operated, as will be clearly understood, the main valve will open and force the check valve 39 upwardly until the top of the flange 42 thereof engages an annular flat rib 43 on said cover member 21, said rib having a radial groove 43^a in one side for a purpose to be hereinafter described.

In order to provide means for restoring the pressure in the control chamber after the flush has been operated, a by-pass is provided in the side of the casing opposite the inlet port 11. This by-pass comprises a rotary plug 44 having a longitudinal passage 45 communicating with the main chamber, said passage 45 opening into a transverse passage 46 which goes entirely through the plug and is connected at its upper end with an inclined passage 47 in the flange 19 of the body member. The passage 47 leads to a second inclined passage 48 in an enlarged boss 49 of the cover member 21, and said inclined passage 48 communicates with the interior of the control chamber.

In order to provide means for changing the period of flow of the flush valve, a slot 50 may be provided in the outer face of the plug 44 for manipulation by a screw driver. The plug 44 may be locked in any desired adjusted position by means of a lock bushing 51 which may be screwed into a surrounding threaded recess in the body member 10 by means of a spanner wrench or other suitable tool which is adapted to engage in a pair of side holes 52 of said bushing 51.

In operation, when it is desired to flush the valve, the button 31 will be pressed downwardly. This will permit a small quantity of water to escape from the releasing chamber enclosed by the tubular section 23, out through the apertures 24^a in the upper reduced section 24 and into the space outside of the cover member 21. The water

which has thus escaped will then flow down to the outlet port 12 through a passage, not shown, in the body member 10.

As will be understood, the water escaping from the releasing chamber will reduce the pressure in the control chamber, and this will allow the unbalanced pressure of the water in the main chamber to act upon the diaphragm 17 and raise the main valve 14 off of its seat. A flushing stream will then be permitted to flow from the inlet port 11 to the outlet port 12 and said stream will continue until the pressure in the control chamber has been restored to normal by the slow leakage of water from the main chamber through the by-pass into the control chamber. The main valve, when it rises, will force the check valve member 39 upwardly into contact with the annular rib 43 on the cover member 21, and said check valve member 39 will be held in contact with said rib by the pressure of the water underneath as long as the releasing valve remains open. After the release valve has closed, however, the check valve member 39 will drop from its upper seat on the annular rib 43, generally in two to four seconds, this being permitted by the leakage by said rib through the radial groove 43^a.

In the modified form of the invention, shown in Fig. 2, the valve-operating mechanism comprises a curved inverted hook-shaped lever 53, said lever having a convex handle section 54. The lever 53 is pivoted on a pin 55 mounted in a pair of wing members 55^a extending upwardly from a collar member 56, said collar member 56 being threaded upon the top of the outer shell 57 of the flush valve. The hook section 53 is provided on its top with a depending plug 58 adapted to engage a button 59 which is similar in all respects to the button 31, previously described for the first form of the invention. The collar member 56 is adapted to be held in adjusted position by a set screw 60 and has a second pair of wing members 61 on the side opposite from the wing members 55^a, said wing members 61 serving to guide the hook-shaped lever 53.

In the form of the invention shown in Fig. 3, the flush is operated by an oscillating handle 62 which may be of porcelain or of any other durable waterproof material, and said handle 62 is connected to a rod 63 having a rounded head section 64 which is adapted to engage a piston member 65 located within a chamber 66. The piston member 65 has a rearwardly extending shaft 67, which extends into a hollow dome section 68 into engagement with one arm 69 of a bell-crank lever 70. The bell-crank lever 70 is pivoted at 71 to the dome 68 and has its other arm 72 lying horizontal and in engagement with a button 73 which is similar to the buttons 31 and 59, previously de-

scribed. The dome section 68 is held upon the shell 74 of the flush valve by a nut 75, said nut being provided with left and right hand threads at its top and bottom portions, respectively. By means of this construction, the dome 68 may be twisted about the shell 74 and locked with the handle 62 pointing in any desired direction. A collar member 76 is adapted to surround the chamber 66 for holding the handle in position and a spiral spring 77 is located within said chamber 66 for normally maintaining the handle 62 in a horizontal position, as shown in Fig. 3.

15 While there have been disclosed in this specification three forms in which the invention may be embodied, it is to be understood that these forms are shown for the purpose of illustration only, and that the 20 invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

30 1. In a flush valve, a main chamber, a control chamber and a releasing chamber, a flexibly-supported valve separating said chambers, means for suddenly releasing a small quantity of water from said control chamber whereby the valve will rise and start the flushing stream, means for slowly restoring the pressure in said control chamber, and a check valve in said control chamber having a portion extending into said releasing chamber for restricting the escape of water from said control chamber after said flexibly-supported valve has opened.

2. In a flush valve, a main chamber, a control chamber and a releasing chamber, a flexibly-supported valve separating said chambers, means for releasing a small quantity of water from said control chamber whereby the valve will rise and start the flushing stream, means for slowly restoring the pressure in said control chamber, and a check valve in said control chamber having a portion extending into said releasing chamber for restricting the escape of water from said control chamber after said flexibly-supported valve has opened, said check valve being held on its seat by the pressure of the water in said control chamber as long as the releasing means is being operated.

3. In a flush valve, a main chamber, a control chamber and a releasing chamber, a flexibly-supported valve separating said chambers, means for releasing a small quantity of water from said control chamber whereby the valve will rise and start the flushing stream, means for slowly restoring

the pressure in said control chamber, and a check valve in said control chamber having a portion extending into said releasing chamber for restricting the escape of water from said control chamber after said flexibly-supported valve has opened, said check valve being held on its seat by the pressure of the water in said control chamber as long as the releasing means is being operated, said check valve being adapted to fall by gravity to its original position when the operation of said releasing means is stopped.

4. In a flush valve having a main chamber, a control chamber, a releasing chamber, and a by-pass, a flexibly-supported valve separating said chambers, means for releasing a small quantity of water from said control chamber to reduce the pressure therein and permit said valve to open and start the flush, and a check valve in said control chamber having a portion extending into said releasing chamber for restricting the flow of water from said control chamber as soon as said flexibly-supported valve is opened.

5. In a flush valve having a main chamber, a control chamber, a releasing chamber, and a by-pass, a flexibly-supported main valve separating said chambers, a releasing valve for permitting the escape of water from said control chamber whereby the greater pressure in said main chamber will cause the main valve to open, a check valve in said control chamber having a portion extending into said releasing chamber carried by said main valve and adapted to close when said main valve is raised, said check valve when closed serving to restrict the flow of water from said controlling chamber to said releasing valve.

6. In a flush valve having a main chamber, a control chamber, and a by-pass, a flexibly-supported main valve separating said chambers, a releasing valve for permitting the escape of water from said control chamber whereby the greater pressure in said main chamber will cause the main valve to open, said main valve having an upwardly extending member, a tubular cup-shaped check valve surrounding said upwardly extending member, said check valve having a flange at its base, and a seat for said flange on the cover of said control chamber.

7. In a flush valve having a main chamber, control chamber, and a by-pass, a flexibly-supported main valve separating said chambers, a releasing valve for permitting the escape of water from said control chamber whereby the greater pressure in said main chamber will cause the main valve to open, said main valve having an upwardly extending member, a tubular check valve surrounding said upwardly extending member, said check valve having a flat flange at

its base, and a seat for said flange on the cover of said control chamber.

8. In a flush valve having a main chamber, a control chamber, and a by-pass, a flexible main valve separating said chambers and being adapted to permit a flushing stream to flow from the inlet to the outlet of said flush valve, said control chamber having a cover, said cover having a tubular upwardly extending section, a releasing valve closing the upper end of said tubular section, a check valve having a body portion fitting within said tubular section, said check valve having a bottom flange and said cover having a seat for said flange whereby the escape of water from said control chamber will be checked as long as the releasing valve is held open.

9. In a flush valve having a main chamber, a control chamber, and a by-pass, a flexible main valve separating said chambers and being adapted to permit a flushing stream to flow from the inlet to the outlet of said flush valve, said control chamber having a cover, said cover having a tubular upwardly extending section, a releasing valve closing the upper end of said tubular section, a check valve having a ribbed outer surface slidable within said tubular section, said check valve having a bottom flange, and said cover having a seat for said flange whereby the escape of water from said control chamber will be checked as long as the releasing valve is held open.

10. In a flush valve having a main chamber, a control chamber, and a by-pass, a flexible main valve separating said chambers and being adapted to permit a flushing stream to flow from the inlet to the outlet of said flush valve, said control chamber having a cover, said cover having a tubular upwardly extending section, a releasing valve closing the upper end of said tubular section, a check valve fitting within said tubular section, said check valve having a bottom flange, and said cover having a depending seat for said flange whereby the escape of water from said control chamber will be checked as long as the releasing valve is held open.

11. In a flush valve having a main chamber, a control chamber, and a by-pass, a flexible main valve separating said chambers and being adapted to permit a flushing stream to flow from the inlet to the outlet of said flush valve, said control chamber having a tubular cover, a releasing valve closing the upper end of said cover, a check valve fitting within said tubular cover, said check valve having an outstanding flange, said cover having a depending rib to form a seat for said flange, and said rib having a narrow groove to permit slow leakage of liquid past said flange.

In testimony whereof, we have affixed our signatures to this specification.

WILLIAM H. CADWELL.
JOHN OTT.
